GRID SPRAY NOZZLE

Ervin J. Nutter, Dayton, Ohio

Application August 5, 1946, Serial No. 688,414

8 Claims. (Cl. 244—136)

(Granted under the act of March 3, 1883, as
amended April 30, 1928; 370 O. G. 757)

1

The invention described herein may be manufactured and used by or for the Government for governmental purposes without payment to me of any royalty thereon.

This invention relates to grid spray nozzles constructed and arranged to form Venturi passage means through which the flow of air is utilized to draw spray material therefrom and be diffused in atomized form.

Many different types of spray nozzle devices are known for distributing spray material in which the spray material is ordinarily emitted from the spray nozzle means by gravity or forced therefrom by a pressure pump. Many forms of spray nozzles have been produced to decrease the droplet size of the issued spray since a decrease in droplet size increases the efficiency of the spray. Such forms of breaking up the spray material have included especially designed nozzle heads, spray breaker bars, and whirling ported discs, or application of pressure to the spray material, and the like, to accomplish desirable atomization. While these devices have been successful in operation continued efforts have been made to obtain a higher degree of atomization of spray material to get greater efficiency without including a burdensome amount of machinery, as pressure pumps, spray breaker bars, etc. Where spraying devices are used on aircraft the necessity of using pressure pumps, spray nozzle attachments, and the like, in order to obtain good spraying qualities, is objectionable since the aircraft operating load is increased.

The present invention of the grid spray nozzle is shown and described as applicable to aircraft merely by way of illustration, although it may be attached to other movable vehicles, or it may be used in a stationary manner, in which the flow of air through a grid nozzle of streamlined fluid conduits, arranged to form Venturi passages therebetween having orifices at the optimum region of high velocity and low pressure air in the Venturi passages, is operable to cause the spray material to be drawn through the orifices at right angles to the air stream at high velocity and shorn off and diffused to produce atomization of the spray material into very finely divided droplets. It has been found that the grid nozzle of this invention gives droplet sizes approximately one-half that of other well known types. The grid spray nozzle of this invention is very simple in design, is adapted for a very large range of flow rate and air flow speeds, and does not require pressure pumps, special nozzle orifice heads, or nozzle attachments for efficient operation.

2

It is a primary object of my invention to provide a grid spray nozzle that utilizes the action of air flow through the grid nozzle to draw the spray material therefrom in atomized form.

It is another object of this invention to atomize spray material by passing a stream of air through a grid of fluid nozzle conduits, formed to provide Venturi passage means therebetween, for drawing the spray material out of the nozzle conduits and diffusing it.

A further object of this invention is the provision of a grid spray nozzle of parallel streamlined conduits constructed and arranged to form Venturi passage means therebetween with orifices in the conduits at optimum points of high velocity and low pressure wherein air flowing through the grid nozzle will pull the spray material from the conduits in an atomized spray.

A still further object of this invention is to provide a grid spray nozzle for aircraft having a streamlined manifold means attachable to the aircraft and in communication with a supply tank for supplying spray material to a multiple of connected axially parallel streamlined nozzle conduits, the streamlined nozzle conduits having their major cross-sectional axes parallel and arranged in the same streamlined manifold to form Venturi passage means therebetween and orifices arranged in the streamlined nozzle conduits substantially in the region of least Venturi passage area at right angles to the air flow wherein the flow of air through the grid nozzle draws the spray material therefrom and diffuses it to produce a fine atomized spray.

Other objects and advantages will become apparent as the description proceeds taken in conjunction with the accompanying drawings, in which:

Fig. 1 is a view of an airplane in broken lines showing one form of the grid spray nozzle, according to the invention, attached thereto.

Fig. 2 is a front view of the form of the grid spray nozzle shown in Fig. 1;

Fig. 3 is a cross-sectional view taken along the line 3—3 of Fig. 2 looking in the direction of the arrows;

Fig. 4 is an end view of the embodiment shown in Fig. 2;

Fig. 5 shows another form of a grid spray nozzle;

Fig. 6 is a top plan view of the embodiment shown in Fig. 5;

Fig. 7 is an end view of the embodiment shown in Fig. 5;

Fig. 8 is another embodiment of the grid spray nozzle;

Fig. 9 is still another embodiment of the grid spray nozzle;

Fig. 10 is a top view of Fig. 9;

Fig. 11 is a cross-sectional view taken along the line 11—11 of Fig. 9, looking in the direction of the arrows;

Fig. 12 is a broken-away view of the side of the streamlined nozzle conduit that forms one wall of the Venturi passage of the nozzle illustrated in the above figures;

Fig. 13 is an enlarged cross-sectional view of the streamlined nozzle conduit illustrated in the above figures;

Fig. 14 is an enlarged cross-sectional view of another modification of a nozzle conduit; and

Fig. 15 is an enlarged cross-sectional view of another form of a nozzle conduit.

Describing the invention more in detail, referring particularly to Fig. 1, there is shown an airplane in broken lines, generally designated by the reference character 21, with a preferred embodiment of the grid spray nozzle 22 of this invention operatively attached to the underside of the fuselage thereof as by hanger brackets 23 fastened to the grid spray nozzle 22 at 24 and to the airplane fuselage by a plate 25 in any well known manner. The grid spray nozzle 22 is supplied with spray material by a conduit 26 connected to a spray material supply tank (not shown) within the fuselage of the airplane. A throttle control valve (not shown) is conveniently placed in conduit 26 in order that an occupant of the airplane may control the flow of the spray material in the well known manner.

The preferred embodiment of the grid spray nozzle, as shown in Figs. 2, 3, and 4, comprises a fluid manifold 27 having a streamlined cross-sectional configuration forming a head portion 28 and a tail portion 29. The upper end of the manifold 27 has a flange 30 for attachment to the spray material supply conduit 26 of the airplane shown in Fig. 1, or for attachment to a supply conduit of any other desirable spray equipment. The lower end of the manifold is closed by a flat plate 31. Spray nozzle conduits or tubes 32 extend in fluid conducting parallel relation from diametrically opposite sides perpendicular to the major diametrical axis of the manifold 27 and are streamlined in cross-section forming head portions 33 and tail portions 34 that lie in the same relative major axis longitudinal direction as the head and tail portions of the streamlined manifold 27. The outer extremities of the nozzle conduits 32 are closed by means of flat plates 35 that extend above the nozzle conduits to facilitate attaching the grid spray nozzle to spraying equipment. The flat plates 35 have openings over the nozzle conduit ends with removable plugs 36 therein for use in inspecting, draining, or cleaning the nozzle conduits 32. The openings thus formed between the nozzle conduits 32, with the head and tail portions 33, 34 all lying in the same relative direction, are constricted to form Venturi passages. Elongated slot orifice openings 37 are arranged at intervals along the nozzle conduits 32, in the region where the head and tail portions 33, 34 of the nozzle conduits 32 meet, opening into the Venturi passages to provide communication between the interior of the nozzle conduits 32 and the Venturi passage. The orifice openings enter at right angles to a tangent of the

exterior surface of the nozzle conduit to permit spray material to be drawn out at right angles to the airstream. The wall portion of the outermost nozzle conduits, that is removed from the Venturi passage means is imperforate.

The grid spray nozzle may, where desirable, be made in sections consisting of a manifold section with a single opposed nozzle conduit on each side thereof and individual end plates over each nozzle conduit end. Such sections may be piled to obtain the desired size of grid spray nozzle and fastened together in any well known manner, as for example, the manner of fastening the sections of a common heat exchanging steam or hot water radiator. The sections are illustrated as being connected at 38 and 39.

Figs. 5, 6, and 7 show another modification of a grid spray nozzle in which two streamlined manifolds 41 and 42 are used having connecting flanges 43 and 44, respectively, for attachment to a spray material supply conduit in the well known manner. Streamlined nozzle conduits 45 are connected between the streamlined manifolds 41 and 42 in parallel spaced fluid conducting relation with the head portions of the streamlined manifolds and the nozzle conduits lying in the same relative direction in the manner described of these elements in Figs. 2, 3, and 4. Caps 46 on the bottom ends of the streamlined manifolds 41 and 42 are removable for inspecting, draining, or cleaning of the manifolds while caps 47 on one of the streamlined manifolds are removable for inspecting and cleaning of the nozzle conduits 45. The nozzle conduits 45 have orifices in their adjacent portions entering into the Venturi passage formed by the nozzle conduits in the same manner as described above of Figs. 2, 3, and 4. Obviously this modification of a grid nozzle may be made in sections in the manner described above, if so desired.

The modification shown in Fig. 8 comprises a streamlined manifold 48 adapted to be suspended vertically from some spray material supply means by the flange 49. Streamlined nozzle conduits 50 are attached in parallel spaced fluid conducting relation on one side of the manifold 48 with the head portions of the manifold and the nozzle conduits arranged in one direction as described of the corresponding elements in Figs. 2, 3, and 4. The outermost ends of the nozzle conduits 50 are closed off by a flat plate 51. Orifices are arranged along the nozzle conduits 50 to permit fluid in the nozzle conduits to flow outwardly into the Venturi passages formed between these conduits in the manner described of the orifice arrangement in these parts with reference to Figs. 2, 3, and 4. Here again this form of grid spray nozzle may be made in sections if desirable. Inspection, draining, or cleanout plugs 52 and 53 are conveniently placed in the manifold 48.

The embodiment shown in Figs. 9, 10, and 11 comprises a streamlined inverted T-shaped manifold 54 adapted to be attached to a spray material supply conduit by the flange 55. Depending vertically from the horizontal portion of the inverted T-shaped streamlined manifold in fluid conducting relation are spaced parallel nozzle conduits 56 streamlined in cross section with the head portions arranged in the same relative direction as the manifold head portion as set forth in the description of the corresponding elements in Figs. 2, 3, and 4. The outer ends of the nozzle conduits 56 are closed as by a flat plate 57. Removable plugs 58 and 59 in the ends of the nozzle conduits 56 and in the manifold, respectively, are

for inspecting, draining, or cleaning purposes. Orifices 60 are arranged along the nozzle conduits 56 opening into the Venturi passages in the same manner as described of the orifices 37 in Figs. 12, 13, and 14. The embodiment shown in Figs. 9, 10, and 11 may be constructed in sections and piled to produce the grid spray nozzle as described of the foregoing modifications, if desirable.

Fig. 12 shows a Venturi wall cutaway plan view of the preferred type of a nozzle conduit 61 with elongated slot orifices 62 therein, as used in the above-described embodiments, particularly shown in Figs. 3 and 11. The nozzle conduit elongated slot orifices are known to be very efficient in emitting the spray material; although rectangular or round, drilled or punched holes may be used where particular application shows the need or if there are preferences.

Fig. 13 shows the streamlined nozzle conduit 61 of Fig. 12, for use as one of the intermediate nozzle conduits, in enlarged cross section. The nozzle conduit 61 has the orifices 62 therealong, equivalent to the orifices 37 in Fig. 3, in the region where the head portion 63 and the tail portion 64 meet entering normal to a tangent of the outer surface thereof. Other types of streamlined nozzle conduits may be used as shown in Figs. 14 and 15 in which the nozzle conduits 65 and 66, respectively, have orifices 67 and 68, respectively, in the region of the juncture of the head and tail portions. In the grid assembly, air flows over these nozzle conduits will be at its highest velocity and lowest pressure in the region of the orifices which will create a vacuum in the orifices to draw spray material out into the airstream. The shearing off of the spray material at the orifices and the subsequent reduction in velocity and increase in pressure of the mixture in the diffusion portion of the Venturi passage causes atomization of the spray material into finally divided droplets.

The number of nozzle conduits shown used in the several embodiments are known to produce good spraying results although any number may be used in designing the grid nozzle for particular spraying purposes.

The method of fabricating the grid spray nozzle may be effected by welding, bolting, threading, or clamping in well known manners, as preferable. The grid nozzle may be manufactured from any metal, fiber, or plastic material capable of being formed, cut, and fastened. If it is made of metal it may be made of virgin metal or alloy to withstand any corrosive liquids to which it may be subjected, or it may be plated in any manner either before or after fabrication to withstand corrosion or erosion, or to improve appearance.

In operation, a grid spray nozzle, according to the present invention, operatively attached to a spray material supply means and adapted to have a stream of air to flow therethrough will cause spray material to be emitted therefrom. By way of illustration these conditions may be produced by attaching the grid spray nozzle to a movable vehicle, as an airplane shown in Fig. 1, which will in flight cause an airstream to flow through the grid spray nozzle. The air flowing through the grid spray nozzle passes through the constricted area of the Venturi passages between the nozzle conduits which increases its velocity and reduces the pressure and pulls the spray material outwardly through the orifices at right angles to the airstream. The orifices are located along the nozzle conduits, as heretofore described, where the optimum condition of diffusion can be obtained in

the Venturi passage means. The action of the airstream through the Venturi passages drawing the spray material outwardly into the airstream diffuses it in the surrounding atmosphere leaving it to fall on the area to be sprayed. The flow rate of the spray material may be controlled by an occupant of the airplane by regulating a throttle valve (not shown) at some place in the spray material supply conduit.

While the grid spray nozzle is illustrated as being used on a movable vehicle as an airplane it is to be understood that it may be made stationary and a stream of air forced through the grid to produce the desirable spraying results.

The grid nozzle is simple of design and so constructed that it may be readily adapted for very large range of flow rates, droplet sizes, and air flow speeds. The adoption of nozzle conduits spaced in the grid nozzle to form long rectangular flow sections is an important feature in spraying. The position of the grid nozzle in an airstream provides sufficient head to the spray material by the passage of air through the Venturi passages obviating the necessity of other equipment as pumps or pressure devices to produce an even flow rate. Although the grid nozzle appears to have a large frontal area, the airstream drag is cut to a minimum because of the recovery in the expanding Venturi passage.

While I have shown and described certain simple embodiments of the invention it is to be understood that many modifications, producing changes in details and construction, may be made without departing from the spirit and scope of my invention and I desire to be limited only by the appended claims.

I claim:

1. A grid spray nozzle device comprising, a plurality of spaced parallel fluid conduits connectible to spray material supply means having their adjacent portions constructed and arranged to form Venturi passage means therebetween, and orifices in the said fluid conduits at the throat section of the said Venturi passage means whereby the flow of air through the grid spray nozzle will pull fluid spray material outwardly therefrom in atomized form.

2. A grid nozzle spraying device, fluid comprising, conduits streamlined in cross-section arranged in spaced parallel relation, the major axes of their cross-sections being parallel and the minor axes of their cross-sections being adjacent the forward respective ends of the same major axes to form Venturi passage means therebetween, orifices in the said conduits in the region of least cross-sectional area of the said Venturi passage means, and manifold means connecting the said streamlined fluid conduits in fluid conducting relation for supplying spray material to the said orifices which spray material is atomized by air flowing through the said Venturi passage means of the grid nozzle.

3. A fluid spray device comprising, streamlined manifold means adapted to be connected to a source of fluid supply and exposed to a relatively moving airstream, at least two discharge tubes of streamlined cross-section connected to the said manifold means in fluid conducting relation and having the major axes of their cross-sections parallel to each other and to the airstream, said discharge tubes being positioned in the airstream and spaced to form Venturi passages therebetween, and ports in the said tubes for discharge 70 of fluid into said Venturi passage means at the

throat section thereof to distribute spray fluid in atomized form.

4. A fluid spray device adapted to be used on aircraft so as to discharge spray fluid into the relatively moving airstream comprising, a source of fluid supply adapted to be carried by the aircraft, streamlined manifold means connected to said source of supply and exposed to the airstream, at least two discharge tubes of streamlined cross-section connected to the said manifold means and having the major axes of their cross-sections parallel to each other and to the airstream, said discharge tubes being positioned in the airstream and spaced to form Venturi passage means therebetween, and ports in said tubes for discharge of fluid into said Venturi passage means at the throat section thereof.

5. A fluid spray nozzle device adaptable for use with aircraft so as to discharge spray fluid into the relatively moving airstream comprising, a source of fluid supply adapted to be carried by the aircraft, a streamlined manifold connected to the said source of supply and exposed to the airstream, discharge conduits of streamlined cross-section disposed in parallel fluid conducting relation from opposed side surfaces and substantially perpendicular to the cross-sectional major axis of the said streamlined manifold, plate means closing the outer ends of the said discharge conduits with upstanding extensions for connection to the aircraft, said discharge conduits being positioned in the airstream and spaced to form Venturi passages therebetween, and orifices in the said discharge conduits for emitting fluid into said Venturi passages at the throat section thereof upon the passage of air therethrough.

6. A fluid spray nozzle device adapted to be used on aircraft so as to discharge spray fluid into the relatively moving airstream comprising, a source of fluid supply adapted to be carried by the aircraft, discharge tubes of streamlined cross-section disposed in parallel relation with their cross-sectional minor axes lying in the same plane perpendicular to the airstream, said discharge tubes being positioned in the airstream and spaced to form Venturi passages therebetween, orifices in the said discharge tubes for discharging fluid in the throat section of the Venturi passages, and a streamlined manifold connected in fluid conducting relation to each of the opposite ends of said discharge tubes, said

streamlined manifolds being in fluid communication with said fluid supply and each having its cross-sectional major axis parallel to the airstream.

5 7. A fluid spray nozzle device adapted to be used on aircraft so as to discharge spray fluid into the relatively moving airstream comprising, a source of fluid supply adapted to be carried by the aircraft, an inverted T-shaped manifold being 10 streamlined in cross-section exposed to the airstream and having its stem portion connected in fluid conducting relation with the said fluid supply, spray nozzle conduits of streamlined cross-section depending in parallel relation from the cross-bar of the inverted T-shaped manifold, said spray nozzle conduits being positioned in the airstream and spaced to form Venturi passages therebetween, and ports in the said spray nozzle conduits for discharging fluid into said Venturi passages at the throat section thereof.

20 8. A grid nozzle spraying device adapted to issue atomized spray fluid into a relatively moving airstream comprising, manifold means of streamlined cross-section exposed to the airstream with the cross-sectional major axis thereof being parallel and the minor axis thereof being forward relative to the major axis and to the airstream, said streamlined manifold means adapted to be connected to a spray fluid supply, a 25 plurality of tubes of streamlined cross-section exposed to the airstream extending laterally in axial parallel relation from the said manifold means substantially perpendicular to the cross-sectional major axis thereof and with the cross-sectional minor axes being forward relative to the airstream to form Venturi passages therebetween, said orifices arranged along the said tubes for discharging spray fluid into the throat section of the said Venturi passages.
